UNITED STATES PATENT OFFICE.

HENRY F. YOE, OF DETROIT, MICHIGAN.

DESIGN FOR A PANIC BOLT.

Application filed January 5, 1924. Serial No. 8,251. Term of patent 7 years.

To all whom it may concern:

Be it known that I, HENRY F. YOE, a citizen of the United States of America, residing in the city of Detroit, Wayne County, Michigan, have invented a new, original, and ornamental Design for Panic Bolts, of which the following is a specification, reference being had to the accompanying drawing, forming part hereof.

I claim:

The ornamental design for a panic bolt, as shown.

HENRY F. YOE.
